RAILWAY WHEEL CHECKING DEVICE

Marion W. Gieskieng, Denver, Colo.

Original application February 4, 1948, Serial No. 6,310, now Patent No. 2,574,474, dated November 13, 1951. Divided and this application August 20, 1949, Serial No. 111,487

7 Claims. (Cl. 246—246)

1

This invention relates to a damaged wheel checking device for railways, and this application is a divisional application of Serial No. 6,310, now Patent Number 2,574,474, issued November 13, 1951, co-pending herewith. Many wrecks are caused by broken wheel flanges and broken wheel treads. It is difficult to locate all of these breaks by mere visual inspection. It is also impossible at present to inspect the wheels while the train is in motion.

The principal object of this invention is to provide a simple and highly efficient wheel checking device which will automatically inspect and locate damaged wheels on a train while the latter is in transit.

Other objects and advantages reside in the detail construction of the invention, which is designed for simplicity, economy, and efficiency. These will become more apparent from the following description.

In the following detailed description of the invention, reference is had to the accompanying drawing which forms a part hereof. Like numerals refer to like parts in all views of the drawing and throughout the description.

In the drawing:

Fig. 1 is a plan view of a section of railway track modified to incorporate the damaged wheel indicating circuits of this improved wheel checking device for detecting broken wheel rims;

Fig. 2 is an enlarged cross-section, taken on the line 2—2, Fig. 1, illustrating the position of conventional car wheels in place on the track;

Fig. 3 is a section through a track rail, arranged for indicating broken wheel flanges with the improved checking device; and

Fig. 4 is an enlarged detail section showing the attachment of a contact strip used in this invention.

In the drawing a conventional car wheel rim is indicated at 10 with its flange at 11.

The present wheel checking device is designed for indicating both broken wheel flanges and damaged rims. In Figs. 1 and 2 one arrangement for indicating broken rims is illustrated. This arrangement consists of a special section of track of any desired length, but at least of sufficient length to exceed the circumference of the largest wheel to be checked.

This section of track consists of two outer easer rails 12, two inner gauge rails 13 and two inner guard rails 14. The three rails at each side of the track are maintained in fixed spaced relation by means of a filler strip 15, suitable spacers 16, and tie bolts 17. The inner edges of the

2

gauge rails 13 are set at the standard gauge and the outer edges of the easer rails 12 substantially align with the outer edges of the wheel rims 10. The flangeways between rails 13 and 14 are standard width.

In applying this invention, the top of each gauge rail 13 is lowered out of contact with the rim 10 of the normal wheel and the top is mortised to receive a contact strip 18 supported from the rail upon suitable electric insulation 19. The strips 18 are preferably formed from hardened, wear-resisting steel or other hard metal. The insulation 19 may be of any suitable type capable of preventing the passage of electric current and of supporting relatively great weight, such as pressed fiber or the like.

The upper surfaces of the strips 18 are positioned sufficiently far below the upper surfaces of the easer rails 12 so that they will not contact the tread of a normal wheel, as shown in Fig. 2 preferably about $\frac{3}{8}$ " below the latter. Should the portion of the rim 10 which rides on the easer rail 12 be broken away or otherwise damaged, the entire wheel will drop sufficiently to cause the tread to contact the strip 18. This contact is employed to close an electrical circuit to any suitable indicating device or signal.

One circuit for this purpose is illustrated in Fig. 1, there being a similar independent circuit 30 for each side of the track. Each circuit preferably employs a relay 20 operating an armature 21 between an opening contact 22 and a closing contact 23. The relay arrangement is such that the armature will close with the closing contact 23 before it breaks with the opening contact 22. A battery 24 or other source of power is provided. The capacity of the battery is such as to overload the relay 20.

A conductor 33 leads from the contact strip 18 to the opening contact 22 and a first battery conductor 25 leads from the battery, through a resistance 26, to the closing contact 23. A rail conductor 27 leads from the rail 12 to the battery conductor 25 between the battery 24, and the resistance 26. A first signal circuit wire 28 leads from the relay 20 and a second signal circuit wire 29 leads from the armature 21. A second battery conductor 30 leads from the other pole of the battery 24, through a switch 31, to the first signal circuit wire 28. The other side of the relay 20 is connected to the second signal circuit wire 29 by a connection 32.

The operation of the device is as follows: should a break in the rim 10 roll over the rail 12 it will allow the entire wheel to drop into contact with

the strip 18. This throws the full battery charge through the relay 20, through conductors 33, 29, 32, 28, 30, 25, and 27. This snaps the armature 21 against the closing contact 23, which substitutes the resistance 26 for the rail and strip conductors 27 and 33. A circuit is now completed to the signal circuit wires 28 and 29 from the battery 24 through the conductors 30 and 25 and through the resistance 26 and armature 21. The signal circuit may be employed for operating any type of visible or audible signalling or recording device such as indicated diagrammatically by a bell 43 to indicate a broken rim exists on one side or the other of the track. After the indication has been recorded, the circuit to the relay is 15 broken at the switch 31 and returns to normal.

For indicating a broken flange a second section of track is prepared similar in length to the section of Fig. 1 and having a cross section at each rail as indicated in Fig. 3. The broken flange indicating track consists of two gauge rails 34 spaced at the proper track gauge and in alignment with the gauge rails 13 previously described. A guard rail 35 is positioned inside of each gauge rail to provide the proper width of flangeway 20 therebetween, the two rails being separated by a flange block 36 and tied together by means of suitable bolts 37. They could, however, be formed as a single unit.

The wheels are supported on their flanges 11 which ride in a flange groove 38 in the tops of the flange blocks 36. The tops of the rails 34 are positioned below their normal position, and below the tops of the guard rails 35, and out of contact with the tread of a normal wheel. The tops of the rails 34 are grooved or mortised to receive second contact strips 39 mounted in suitable electrical insulation 40.

The second strips 39 are formed from hard metal such as hardened steel similarly to the first strips 18 and their upper surfaces project slightly above the upper surfaces of the gauge rails 34.

It can be readily seen that if the flange 11 be chipped or broken it will allow the wheel tread to descend onto the strip 39 closing a circuit therewith. The circuits may be similar to those shown in Fig. 1 in which event the conductors 33 would be connected with the strip 39 and the conductors 27 would be connected with the flange strip 36, in any desired manner.

The strips 18 and 39 may be secured to their respective rails in any desired manner. One method is shown in Fig. 4, in which cap screws 41 are counter-sunk into the strips and threaded into the rails. The cap screws are insulated from the strips by means of suitable surrounding insulation 42.

The purpose of the resistance circuit is: first, to allow a momentary impulse of the full battery strength to close the relay so as to obtain a quicker closing action to facilitate rapid train movement; and second, to hold the relay closed sufficiently long after the momentary closing impulse has ceased to allow ample record to be made of the signal.

As illustrated, both rails of the track are adapted to the improved signal system in the same track section. It is of course possible to have only one rail so adapted at any given point and the other rail adapted at a different point if so desired.

While a specific form of the improvement has been described and illustrated herein, it is desired to be understood that the same may be varied, within the scope of the appended claims,

without departing from the spirit of the invention.

Having thus described the invention, what is claimed and desired secured by Letters Patent is:

1. A broken wheel indicator for a railway wheel comprising: a continuous, fixed, electrical-conducting contact strip extending along beneath the path of said wheel; means contacting the periphery of said wheel and being insulated from said strip and supporting a normal wheel above and out of contact with said strip so that any abnormality in the periphery of said wheel will allow the wheel to descend into contact with said strip; and a signal circuit including said strip and said supporting means for giving an indication when said contact is made.

2. A broken wheel indicator for a railway wheel comprising: a continuous, fixed, electrical-conducting contact strip extending along beneath the path of said wheel; a track member upon which a portion of the periphery of the wheel rolls, said track member being insulated from said strips and being positioned to support a normal wheel in vertically spaced relation to said strip so that any missing portions in the periphery of said wheel will allow the wheel to drop into physical and electrical contact with said strip; and a signal circuit including said strip and said track member for giving an indication of said contact.

3. A damaged wheel checking device for railways comprising: a pair of metallic, wheel-supporting rails for supporting an axle-connected pair of railway wheels, said rails being spaced apart a distance exceeding the normal gauge of said pair of wheels so that only the outer portions of the rims of said wheels will ride on said rails; a continuous, fixed, electrical-conducting, contact member insulated from and positioned inside of, and parallel to, each rail below and in spaced relation to the remaining portions of the rims of said wheels, so that any abnormality in the outer portions of said rims will allow the inner portions thereof to descend into electrical contact with said member; and signal circuits including said members and said rails and arranged to give a signal when said contact is made.

4. A damaged wheel checking device for railways as described in claim 3 having guard rails 50 acting against said wheels to maintain said outer rim portions on said first rails.

5. Means for detecting a broken flange on a railway car wheel comprising: a flange track member along which the flange of said wheel rolls to support the latter; a fixed, continuous, electrical-conducting contact strip positioned below the path of the rim of said wheel, said strip being electrically insulated from said track member; and a signal circuit including said flange track and said contact strip so that when a defective flange allows said rim to drop into contact with said strip, said circuit will be closed to give a signal.

6. Means for detecting a broken flange on a railway car wheel comprising: a flange track member along which the flange of said wheel rolls to support the latter; a fixed, continuous, electrical-conducting contact strip positioned below the path of the rim of said wheel, said strip being electrically insulated from said track member; a relay; an electric circuit including said strip, said relay and said flange track so that when a defective flange allows said rim to drop into contact with said strip, said circuit will be closed to operate said relay; means for holding

said relay closed after said circuit opens; and a signal circuit controlled by said relay.

7. Means for detecting a broken rim on a railway car wheel comprising: a metallic rail positioned adjacent the outer edge of said rim and supporting said wheel; a continuous, electrical-conducting contact strip electrically insulated from said rail and supported below said rim adjacent the inner edge of the latter; and an electrical signal circuit including said strip and said rail so that when a broken portion of the outer edge of said rim allows said rim to descend into

contact with said strip, said signal circuit will be closed.
